UNITED STATES PATENT OFFICE

2,464,355

SHOE AND METHOD OF MAKING SAME

Irving Foster Starner, South Bend, Ind., assignor to Mishawaka Rubber and Woolen Manufacturing Company, Mishawaka, Ind., a corporation of Indiana

Application June 18, 1945, Serial No. 600,021

6 Claims. (Cl. 36—19.5)

1

My invention relates to shoes of the type in which a heel of wood or the like, usually somewhat of a wedge shape in vertical section from front to rear, is contained in a covering that is attached to the margin of the insole and to the lower margin of the shoe upper and extends downwardly along the sides and rear of the heel and is lasted thereunder, shoes of this type being quite commonly known as "Wedgies." Such shoes usually, although not necessarily, have a padlike member extending forwardly from the front end of the wedge heel and similarly encased.

Usually the heel is applied in such shoes while the covering therefor is turned up around the upper, thereby affording access to manipulate the seam where the covering, insole and upper are joined together and insure placement of the heel so that this seam is properly disposed around the margin thereof, but as the covering is thereafter turned down around the heel and must conform to the shape thereof, this procedure is limited to low straight back heels, as a turned up covering for a high heel, especially if it slants under at the back, cannot be turned down conveniently or satisfactorily if the covering is of the proper shape to conform to the contour of the heel.

It has been proposed to turn down the heel covering before the shoe upper assembly is placed on the last, and then apply the heel in place through the open bottom of the turned down covering but that procedure has not been found satisfactory with the heel covering stitched to the insole entirely around the rear as access cannot be had to the seam where the upper, insole and heel covering are joined, and this seam accordingly is oftentimes misarranged.

Also in such shoes the heel covering is usually formed of a single piece of material extending from each side of the shoe vamp around the back of the heel, and this one piece construction of the heel covering not only contributes to the problem of locating a high slanted heel in place but does not permit the economy of material that could be effected if a two piece heel covering were employed.

The principal objects of my invention are to provide an improved procedure for assembling the heel in the heel covering of the above mentioned type of shoes; to insure convenient and proper positioning of the seam where the upper, insole and heel covering are joined together; to permit a two piece heel covering to be employed; and in general to provide an improved

2

shoe structure of the type above mentioned—these and other objects being accomplished as pointed out more fully hereinafter and as shown in the accompanying drawing in which:

Fig. 1 is a side view of a "Wedgie" type shoe constructed in accordance with my invention;

Fig. 2 is a longitudinal sectional view through the shoe with portions of the shoe upper broken away;

10 Figs. 3, 4 and 5 are fragmentary sectional views taken on the lines 3—3, 4—4, and 5—5 respectively of Fig. 1;

Fig. 6 is a top view of the heel member showing the layers that are applied on the top face 15 of the heel and also showing the slotting at the rear that may be used with a two piece heel covering;

Fig. 7 is a rear view of the heel member of Fig. 6;

20 Fig. 8 is a fragmentary horizontal section through the rear of the heel member of Figs. 6 and 7 showing the manner of securing the ends of the two piece heel covering therein;

Fig. 9 is a side view of a last showing the initial 25 shoe assembly thereon;

Fig. 10 is a view similar to Fig. 9 showing the manner of inserting the heel member; and

Fig. 11 is a view similar to Fig. 3 but showing an alternative arrangement of the stitched together margins of the insole, upper and covering 30 of the sole and heel.

In the drawing, I have, for illustrative purposes, shown a particular style of "Wedgie" shoe with open toe and open heel although it is to 35 be understood that the invention may be employed with shoes of other styles.

In this illustrated shoe the reference numeral 12 indicates the shoe upper which is secured along its lower margin to the margin of an insole 40 13 which overlies a heel member 14 and forepart pad 15, the heel member 14 and forepart pad 15 being encased in a surrounding covering composed of the two parts 16 and 17 which extend respectively around the rear and along the sides 45 of the heel member 14 and around the front and along the sides of the forepart pad 15 and have their ends overlapped at the opposite sides of the shoe as indicated at 18 in Fig. 1.

These coverings 16 and 17 are attached along 50 their upper margins to the upper 12 and insole 13 and have their lower margins turned in under or lasted onto the bottom faces of the heel member 14 and forepart pad 15 as indicated at 19 and 20 respectively, an outer sole 21 being secured onto the bottom of the heel member and 55

forepart pad and to the lasted edges 19 and 20 of the coverings 16 and 17 in accordance with common practice.

The lower margin of the upper 12 is secured between the downturned margin of the insole 13 and the downturned upper margin of the coverings 16 and 17, preferably by a line of stitches 22 as shown in Fig. 3, all the way around the shoe except at the front toe opening 23 and at the heel where the upper is undercut at 24 to leave only a heel strap 25. At the toe opening the downturned margin of the insole is stitched directly to the downturned upper edge of the covering 17 as shown in Fig. 2 whereas, at the heel opening, in the method of the present invention, the insole margin may be stitched directly to the downturned upper margin of the covering 16 part way back from the forward end of the heel opening or for example from the point 26 to the point 27, at both sides of the shoe and beyond the points 27 the upper edge of the heel covering 16 is turned in over and cemented to the top surface of the heel member 14 in a sort of lasting operation as indicated at 28 in Fig. 5, while the marginal edges of the insole around the corresponding portion of the heel are turned back under as indicated at 29 in Fig. 5 and cemented to the top surface of the heel member 14 and to the inturned edges 28 of the covering 16.

Obviously any stitching of the insole 13 to the covering 16 at the heel opening or beyond the points 26 may be omitted and the top edge of the covering 16 and the margin of the insole cemented to the top surface of the heel 14 and to one another as illustrated in Fig. 5 entirely around the heel opening if desired.

The heel member 14, which is commonly made of wood or other light weight material extends forwardly to approximately the forward extremity of the instep portion of the sole where it is terminated, preferably on a diagonal line corresponding somewhat to the diagonal manner in which a shoe normally bends in walking, the underside of the forward edge of this heel member 14 being beveled as indicated at 30, and this heel member 14 may be of substantial height and of overhanging shape around the rear as illustrated herein to provide a slanting heel which it has been difficult to assemble in the previous procedure of making shoes of this type.

The forepart pad 15 may be of felt or any suitable material, preferably cushiony and capable of bending quite readily and is beveled along the rear edge to match the bevel 30 of the heel member 14 at which place the heel and forepart pad are preferably cemented together.

The insole 13 may be of one or more plies of fabric or the like, two layers of fabric 31 and 32 being shown herein which are preferably secured together adhesively throughout their area, and this insole extends continuously throughout the entire top area of the composite heel 14 and sole 15. A layer of paper 33, of medium cardboard variety is adhesively secured to the top face of the heel member 14 and extends forwardly some distance beyond the diagonal forward end of the heel member 14 as indicated at 34 in Fig. 2, this paper layer 33 being preferably otherwise of dimensions less than the top face of the heel member 14 so as to leave a marginal portion of the top surface of the heel member 14 exposed along the sides and around the rear and affording in effect a marginal seat 35 for the edge portions

of the upper, insole and covering 16 where they are stitched or otherwise joined.

In addition, a thin filler 36 of relatively soft material may be interposed between the insole 13 (composed of the parts 31 and 32) and the paper layer 33 and is substantially coextensive with the latter at the sides and around the rear so that it does not extend onto the marginal seat 35, and all of these parts are adhesively secured to one another in the shoe assembly.

The heel covering 16 may be a single piece of material cut to suitable shape to conform to the shape of the heel member 14 which it is to enclose, and accordingly, when used with a slanting heel such as illustrated herein it is so shaped that when it is turned down it has a corresponding slant and is smaller around the bottom than at the top, it being important that the covering fit snugly the heel contour without any fullness, folds or wrinkles as any such misfitting makes the shoe unsalable.

The heel covering 16, however, may be made of two pieces, seamed at the back if the heel member 14 is made with a recess to accommodate the inturned edges of the seam and insure a neat finished appearance at this place.

I prefer, because of convenience of manufacture and assurance of a neat appearance, to employ a two piece heel covering composed of two side pieces as shown at 16a and 16b in Fig. 8 and construct the heel member 14 with a slit 37 down the back into which the meeting edges 16c and 16d respectively of the two pieces 16a and 16b are tucked and cemented as indicated in Fig. 8.

Other narrow slits 38 may be provided at opposite sides of the slit 37 if desired to afford expansibility of the latter slit to facilitate tucking the edges 16c and 16d into that slit, and it will be understood that with this arrangement, not only is it possible to utilize stock for the pieces 16a and 16b which could not be used for heel coverings 16 of one piece but that with the two pieces 16a and 16b and the tucking in of the edges 16c and 16d these pieces may be pulled tautly against the surface of the heel 14 and cemented thereto in perfectly smooth form fitting manner and with an inconspicuous neat appearing arrangement thereof at their meeting ends.

Preferably the shoe is made with a straight or flat sole 21 as shown herein and without any undercutting at the shank, but it may be made otherwise if desired. For example, the heel member 14 may have the underside of the forward portion arched to provide a somewhat conventional shoe shank form, and the sole 21 may be shaped to conform to this arch and have either an integral or a separate heel lift on the heel portion proper at the rear of the arch as will be readily understood by those versed in the art.

In making the above described shoe, the upper 12, insole 13, and coverings 16 and 17 having been cut or stamped in the proper size and shape, the lower margin of the upper is laid along the appropriate portion of the margin of the insole and the corresponding portions of the margins of the coverings 16 and 17 are laid along the margin of the upper, and these three parts are stitched together along their margins by the line of stitches 22, the stitching being continued around the toe where only the insole and covering 17 are stitched together in view of the opening 23 that is left in the upper, and the stitching also extends to the desired extent at the rear

where the upper is cut away at 24, as for example, to the points 27 at each side of the shoe, it being understood that from the point 26 to the point 27 only the insole and the covering 16 are stitched together.

In this stitching operation the margins of the insole are usually bent downwardly at an angle to facilitate applying the margin of the upper therealong and the coverings 16 and 17 are laid against the upper in what may be regarded as an up turned position, as distinguished from the eventual downturned position—that is with their outer finished sides next to the upper—and it will be understood that the upper 12 may be substantially completed otherwise before this stitching operation and already provided with eyelets, reinforcements, lining, etc. which the finished shoe is to have.

Either the stitching 22 is applied very closely to the edges of the connected parts, or these edges are trimmed off afterward to leave only a very narrow width of stock beyond the stitching to be accommodated in the margin of the shoe sole structure.

At the time of this stitching the forward ends of the covering 16 overlie the rear ends of the covering 17 at opposite sides of the assembly, and at the overlapping places they are thus stitched together by the stitches 22, and when these parts 16 and 17 are subsequently turned down to the positions which they occupy in the finished shoe they are bent sharply just above the seam 22 as indicated at 40 in Fig. 3 and their outer finished faces which were next to the upper 12 in the stitching operation are then outside, and the rear ends of the covering 17 then overlap the forward ends of the covering 16 as shown at 18 in Fig. 1.

After this stitching operation, the paper 33 and filler 36 laminations are cemented onto the bottom of the insole 13, which in the present illustration is composed of the two fabric layers 31 and 32, the filler lamination 36 being preferably first cemented onto the paper lamination 33 after which the composite assembly of paper 33 and filler 36 is applied on the insole and when thus applied and secured in place, this composite assembly serves as a form along the edge of which the stitched together margins of the insole 13, upper 12 and heel covering 16, may be turned down neatly, these latter turned down margins being illustrated in Fig. 4.

The heel covering 16 is then turned down to the position it is to occupy in the completed shoe, and the assembly is applied on a last 41 as shown in Fig. 9 with the covering 16 in an upstanding position around the place where the heel member 14 is to be located, the covering 16, however, being unattached to the insole 13 at the time from the point 27 at one side of the assembly clear around the heel to the corresponding point 27 at the other side so that the covering 16 is loose from the insole 13 at this place.

The margin of the insole 13, around the heel from the point 27 on one side to the point 27 on the other side, which is indicated at 42 in Fig. 9, may then be turned in and cemented against and over the edges of the composite paper 33 and filler 36 assembly, substantially as indicated at 29 in Fig. 5, or this operation may be performed if desired before placing the shoe assembly on the last, the covering 16 being at the time unattached between these points 27, 27 so that this turning in operation may be readily performed.

Then the heel member 14 is slipped rearwardly along the insole 13, somewhat as indicated in 78

Fig. 10, to its proper location on the insole, care being taken to maintain the stub edges of the seam 22 in proper seating position on the margin 35 of the heel from the point 27 to the front end of the heel member 14 which is readily accomplished because of the relatively short distance and the accessibility thereto at the front and rear.

The exposed face of the paper layer 33 and the 10 insole face of the heel member 14 are, of course, coated with cement before the heel is inserted in place and after the heel is properly located the parts are pressed together so as to adhere firmly to one another.

15 After the heel member 14 has been placed in position as above explained, the edges of the covering 16 around the heel between the points 27 are cemented and tucked in between the insole and heel substantially as shown at 28 in Fig. 5, 20 the covering 16 being at the same time fitted snugly around and against the rear of the heel member 14, and the parts are then pressed together so as to afford a neat and permanent connection of the heel member with the insole and 25 also with the inturned parts 28 and 29 between the margin of the heel member and the insole.

Thus a heel with any desired amount of slant or of any shape may be employed as it is merely inserted into the correspondingly shaped rear of 30 the covering 16 which is already turned down to the position it is to occupy in the finished shoe and there is no stretching or distorting of the heel covering which would necessarily occur if the slanted heel covering were left upturned 35 around the shoe upper and then pulled down around the heel after the latter was secured in place. Also by leaving the covering 16 unattached around the heel from the point 27 on one side to the point 27 on the other side and tucking the 40 margin thereof in between the heel member 14 and insole after the heel member is located in place, no seam misplacement can occur as it would be likely to do if the stitching 22 were continued entirely around the rear of the heel.

45 After the heel 14 has been placed in position, the forepart pad 15 is applied and cemented in place, in which operation the forepart pad covering 17 may be either turned up or turned down as desired, and then the lower margins of the 50 coverings 16 and 17 are fastened over and cemented to the composite sole 14, 15 after which the outsole 21 is cemented in place in the usual manner.

Instead of employing for the heel covering 16 a single piece of material which is continuous 55 around the rear of the heel member 14 as contemplated in the above described method, two side pieces 16a and 16b may be employed and the heel member 14 may be formed with a slit 37 down the rear and additional spreader slits 38 60 if desired, for joining the ends of the side pieces 16a and 16b.

With such heel covering, since the rear ends of the parts 16a and 16b may be separated at the time, the heel member 14 is more easily inserted 65 in place and the stitching of the upper margin of the coverings 16a and 16b to the insole margin may be continued farther back to the rear of the heel than with a continuous heel covering 16, or for example, the points 27 at which the stitching 70 is terminated at the opposite sides of the heel may be as far back as 27a in Fig. 1.

With the two piece heel covering, the heel member 14 is slipped in place and cemented to the insole in substantially the same manner as previously described, after which the loose rear ends

of the side pieces 16a and 16b are drawn snugly around the rear of the heel member 14, and cement having been applied to the meeting edges thereof and in the slot 37, these edges are tucked into the slot 37 and thus the rear ends of the side pieces 16a and 16b are secured in place.

Thereafter the loose upper edges between the points 27a are tucked in under the insole and cemented in place in the same manner as in the case of the one piece covering 16 and the shoe is thereafter completed in the manner hereinbefore described.

Instead of turning the seamed edges of the insole 13, upper 12, and coverings 16 and 17 downwardly as shown in Fig. 3, the insole 13 may be left flat at the margin and with no downturned edge, as shown in Fig. 11, and the lower margin of the upper may be turned outwardly as indicated at 43 in Fig. 11. The margin of the covering 17 (or of the covering 16) is, in this arrangement folded back upon itself as indicated at 44 and then bent downwardly as at 45, and the butt edges of the stitched together parts face outwardly as shown in said Fig. 11, instead of downwardly as in the arrangement of Fig. 3, and are covered by the downturned covering 17, and the stitching 22 is vertically or at right angles to the insole instead of horizontally as it is in the arrangement of Fig. 3.

While I have shown and described my invention in a preferred form, I am aware that various changes and modifications may be made therein without departing from the spirit of the invention, the scope of which is to be determined by the appended claims.

What is claimed is:

1. The method of assembling a heel member in an assembly comprising an insole with heel covering attached thereto, said method comprising leaving the heel covering unattached to the insole around the rear of the latter, then inserting the heel member within the heel covering and securing said inserted heel member to the underside of the insole, and then permanently securing the heel covering and insole together at the place where the heel covering was left unattached to the insole as aforesaid.

2. The method of assembling a heel member in an assembly comprising an insole with heel covering attached thereto, said method comprising preparing the assembly with the heel covering attached to the insole along the lateral margins of the latter and separable from the insole at the rear, inserting the heel member within the heel covering against the underside of the insole, then securing the margins of said separable rear portions to the top face of the heel member in closed together relation.

3. The method of assembling a heel member in an assembly comprising an insole with heel covering attached thereto, said method comprising

5 preparing the assembly with the heel covering attached to the insole along the lateral margins of the latter and separable from one another at the rear and cementing to the underside of the insole a stiffener beyond the margins of which the margins of the insole are extended, thus inserting the heel member within the heel covering against the stiffener and adhesively attaching said heel member to said stiffener, then adhesively securing the margins of said separable rear portions to one another and to the top of the inserted heel member.

4. The method of assembling a heel member in an assembly comprising an insole with heel covering attached thereto, said method comprising preparing said assembly with a heel covering composed of two parts which are separable at the rear, applying and cementing to the underside of the insole a heel member having a slot at the rear, and then adhesively securing the separable margins of the two heel covering parts together in said heel member slot.

5. In a shoe of the class described, the combination of an insole having a shoe upper and heel covering stitched to the insole margins, and a heel member secured to the underside of the insole with said heel covering on the sides and around the rear thereof, said heel covering having the upper margins turned in over and cemented to the top of the heel member around the rear of the heel and the insole having downturned margins around the rear thereof overlying and cemented to the said turned in margins of the heel covering.

6. In a shoe of the class described, the combination of an insole having a shoe upper and heel covering secured to the insole margins, and a heel member secured to the underside of the insole with said heel covering on the sides and around the rear of the heel member, said heel covering being composed of two parts and said heel member having at the rear a slot in which the margins of the two parts are turned in and secured together solely by an adhesive.

IRVING FOSTER STARNER.
